MACHINES FOR PRINTING AND ISSUING
TICKETS AND BUSINESS FORMS

Richard I. N. Weingart, Brookville, N.Y., assignor to Burroughs Corporation, Detroit, Mich., a corporation of Michigan

Filed Dec. 17, 1954, Ser. No. 475,940

22 Claims. (Cl. 101—68)

This invention relates to machines and methods for issuing business forms and to forms or tickets issued by the machine and in accordance with said methods.

The general objects of the present invention relate to the issuance of business forms and particularly transportation tickets in such fashion as to avoid the necessity for carrying on hand stocks of preprinted tickets which, by virtue of their nature, represent documents of value, to provide accounting records of the tickets issued from which all essential data may be secured, to insure against falsification of records, and to facilitate the issuance of tickets. In accordance with the invention, a mechanism for issuing tickets and maintaining records is provided which is relatively simple and inexpensive and, hence, is particularly adapted for use at stations, airports, relatively small ticket agencies, etc., where the number of sales of tickets made would not warrant the cost of more elaborate machines. However, as will become apparent hereafter, machines of the type herein disclosed are by no means so limited in their capabilities that they would be inapplicable even to stations, or the like, where large volume sales are involved. Furthermore, the machines are adapted to other than transportation use, though for consistency of description they will be hereafter referred to as for that use.

In brief, the machines of the present invention are arranged to print tickets from sheet stock, which may be in part preprinted, through the use of removable slugs corresponding to particular tickets to be issued. These slugs not only print suitable matters on the ticket strip to form the tickets to be issued, but additionally provide complete printed records of the transactions involved. Furthermore, the machine is arranged to issue, and record the issuance of, tickets of "write-in" type in which certain information must be written in the ticket by the ticket-issuing agent. Such tickets may be involved, for example, when it does not pay to provide at the station of issuance slugs involving the issuance of tickets to small stations or destinations to which the traffic from the issuing station may be quantitatively very low. Write-in operation may also be involved in the case of issuance of pullman or coach reservation tickets, in which instances the ticket issuing agent may be required to ascertain space available and identify on the ticket the particular space sold.

The general objects of the invention outlined above, as well as other objects relating particularly to details of the machine, its operation, procedure in issuing tickets, and the tickets themselves, will become apparent from the following description read in conjunction with the accompanying drawings, in which:

Figure 1 is a general plan view of the operating mechanism of a preferred type of machine, showing, in particular, the mechanism located below a top plate of the machine, with various parts broken away to show details of construction;

Figure 2 is a partial elevation taken on the plane indi-

2

cated at 2—2 in Figure 1, the view being taken in the direction of the arrows;

Figure 3 is a vertical section taken on the plane indicated at 3—3 in Figure 1;

Figure 14 is a vertical section taken on the plane indicated at 14—14 in Figure 9;

30 Figure 15 is in part a section and in part an elevation taken on the broken surface indicated at 15—15 in Figure 9;

Figure 16 is a plan view of the machine with the top plate removed and various other parts broken away to show details;

35 Figure 17 is a plan view of the top of the machine but with portions of the printing box broken away to show elements therewith;

Figure 18 is a vertical section through the machine particularly showing the storage provisions for the ticket strip and record members and illustrating the paths there-of through the operating mechanism;

40 Figure 19 is a perspective view of the upper portion of the machine particularly showing the printing box in opened position for write-in purposes;

Figure 20 is a perspective view of the machine showing the printing box in its normal partially tilted position in which it is ready to receive a slug;

45 Figure 21 is a plan view showing a typical preprinted ticket stock;

Figure 22 is a top plan view of a typical slug provided for use in the machine;

50 Figure 23 is a front elevation of the slug;

Figure 24 is a bottom plan view of the slug;

Figure 25 is a plan view showing the matter printed 55 by a slug on one type of ticket;

Figure 26 is a plan view showing the matter printed on a ticket by a slug which is arranged for the issuance of a round-trip interline ticket;

Figure 27 is a plan view showing matter typically 60 printed on a ticket by a slug designed for the issuance of pullman or similar reservations;

Figure 28 is a plan view of a ticket which is typical of tickets issued for one-way transportation;

Figure 29 is a plan view of a ticket typical of tickets issued for round-trip transportation on a single line;

65 Figures 30 and 31 are plan views showing coupon elements which are associated with the ticket strip for the production of a round-trip interline ticket;

Figure 32 is a plan view showing an assembly of coupon elements associated to provide a round-trip interline ticket;

70 Figure 33 is a fragmentary plan view showing a por-

tion of a ticket journal strip as printed in the machine, there being indicated in this figure certain legends indicative of types of sale;

Figure 34 is a plan view with portions broken away illustrative of a three-ply pullman reservation ticket stock of preprinted type;

Figure 35 is a plan view showing associated pullman reservation coupons as provided by the machine and with certain data written therein;

Figure 36 is a fragmentary plan view of a pullman reservation ticket journal as printed in the machine; and

Figure 37 is a plan view of a commutation ticket which may be issued by the machine.

The preferred form of machine provided in accordance with the invention will be first described, this description being followed by a description of the machine operation and by a description of the types of tickets and the various alternative ticket issuing methods which may be employed in accordance with the invention.

The machine comprises a housing which incorporates various supporting frame elements the arrangement of which will become clear as the description proceeds without the necessity for detailed description of these elements.

Power for operation is provided by a motor 2 the shaft of which through its pinion 4 drives gear 6 which, in turn, is connected to rotate with a pinion 8. A clutch arrangement is provided by a gear 10 arranged to mesh with pinion 8 but having a portion of its circumference cut away to be completed by the teeth on a lever 12 pivoted at 14 to the gear 10 and urged in a counterclockwise direction, as viewed in Figure 3, by a spring 16. The gear 10 is carried by a shaft 11 which furnishes drive to certain parts of the machine as will hereafter appear. The lever 12 is provided with a pin 18 with which is engageable the hook end 20 of a lever 22 pivoted at 24 and normally urged in a clockwise direction, as viewed in Figure 3, by a spring 26. The lever 22 is held in engagement with the pin 18 by means of a lever 28 to which further reference will hereafter be made.

The gear 10 meshes with a gear 30 which is secured to a shaft 32 from which various operations of the mechanism are derived.

A pin 34 carried by lever 22 is arranged to engage a movable switch member 36 to produce circuit closure through the motor 2 by engagement of contacts 38. The shaft 11 is provided with a cam 40 arranged to act upon the roller 42 carried by the pivoted lever 44 which is urged by spring 46 to produce contact between roller 42 and cam 40. The lower end of the lever 44 is also arranged to engage the switch member 36 to close the contacts. The switch member is normally urged into circuit opening position by a spring 45.

Secured to the shaft 32 is a gear segment 48 subtending 180° and arranged to drive through half of a cycle of operation a pinion 50 secured to a shaft to which there is also secured a sprocket wheel 52 over which a chain 54 is trained to drive a second sprocket wheel 56 secured to a transverse shaft 58. A disk 51 secured to pinion 50 is provided with a notch to receive a detent roller 53 carried by a lever 55 urged by a spring 57 to provide a yielding detent action. The shaft 58 is provided with a pair of pinwheels 60 each carrying pins 62 for the drive of a ticket strip T. Edge stripping members 64 embrace portions of the circumferences of the pinwheels 60 to remove and deliver downwardly the perforated edge portions T' of the ticket strip T. A plate 66 is arranged to divert the central main portion of the ticket strip T outwardly of the machine.

The shaft 58 carries the Geneva drive member 68 which cooperates with a driven member 70 to which is secured a pinion 72 meshing with a gear 74 secured to a second transverse shaft 76. The shaft 76 is longitudinally slidably and is urged toward the left, as viewed in Figure 1, by means of a spring 78 to engage a pin 80 carried by shaft 76 within a notch in the end of a sleeve 82. It will

be noted that the pinion 72 is provided with a wide face so that the lengthwise movements of shaft 76 will not disengage the pinion 72 and gear 74. For the purpose of imparting movements to the shaft 76 toward the right, as viewed in Figure 1, to disengage pin 80 from sleeve 82 there is guided in the frame a pin 77 engageable with a head 75 formed on the end of shaft 76. This arrangement permits manual axial movement of the shaft while preventing the projection through the housing of the rotating shaft. The arrangement thus prevents manual interference with the shaft rotation.

The sleeve 82 is provided with a pair of pinwheels 84 provided with pins 86 for the feed of a pair of record strips R and R' which are perforated at their edges. A member 88 serves to hold these strips in engagement with the pins and forms together with a plate 90 an outlet opening for the delivery at the rear of the machine of the record strip R.

The ticket strip T is provided from a bin 92 in the housing, as shown in Figure 18. The severed edges T' of this strip are received in a bin 94. A bin 96 supplies the record strips R and R' which are fan-folded in parallel in the bin. The record strip R' is ultimately delivered to a receiving bin 98 wherein it is automatically refolded. To prevent interference of the several strips with each other, they are fed past spacing rollers 100 and 102 and over plate 103. The edge portions T' are guided to the bin 94 through guide members 104, while a plate 106 serves to control and guide the movement of the record strip R' to the bin 98.

Secured to the shaft 32 are a pair of eccentrics 108 the straps 110 of which are pivoted at 112 to a carriage 114 which is mounted for horizontal sliding movements in the machine frame. A shaft 116 mounted in this carriage is provided with a pinion 118 which meshes with another pinion 120 carried by the carriage and which, in turn, meshes with a fixed rack 122 mounted on a machine frame. The shaft 116 carries a semicircular platen 124 of yielding rubber material which, as will appear, serves to press the several strips against type to effect printing. The carriage 114 is provided with a plate 126 which provides a backing for the writing of information on tickets.

A housing 128, which will be referred to hereafter as a printing box, is provided with ears 130 which serve to mount it pivotally on the ends of shaft 58, this being merely a convenient mounting. The bottom of the printing box 128 is open and mounted therein is a plate 132 provided with lips 134 for the guidance of an introduced slug S. A pair of magnets 136 are fixed above the plate 132 and are arranged to attract and hold upwardly a slug S inserted below the plate 132 which is of non-magnetic material. To the rear of the plate 132 and in position to be engaged by an inserted slug is a slide 138 which is slotted for guidance by pins 140, the slide being urged in a forward direction by springs 143. The slide 138 is provided at one end with a projection 142 which is arranged to cooperate with a shoulder 154 formed on an arcuate link 144 which is slotted at 146 for the passage of a screw 148 to secure it slidably to the printing box 128. The depending portion of the link 144 is provided with an arcuate slot 150 embracing a pin 152 fixed to the machine frame.

A pair of rollers 156 and 158 serve to mount the reeled ends of an inked ribbon C. Knobs 160 and 162 serve for control of movement of the ribbon C. While its movement could be made automatic in obvious fashion, this is unnecessary, the ribbon being advanced manually through manipulation of the knobs as required. The ribbon is guided about rollers 164 and 166 and also about guide strips 168 and 170 provided with slidable guide pins which are urged downwardly by leaf springs 169 and 171 carried by the printing box. The members 168 and 170 also serve for the guidance of a slug S by cooperation with guide slots 172 and 174. In normal conditions prior to actual printing, the space between the plate 132 and

the ribbon C is greater than required for the reception of the slug and the slug is kept from engaging the ribbon C by means of the magnets 132. However, as platen pressure is applied the members 168 and 170 are forced upwardly and serve to hold the slug in positive fashion and in definite position by reason of the guides 172 and 174 which receive projections on the slug as hereafter described. It may be remarked that the member 170 additionally normally holds the ribbon C away from other type surfaces involved in the printing box.

Projecting through the top of the printing box are wheels 176 which carry date designations and are respectively coupled by means of gear trains 178 to corresponding type wheels 180 which are located in the printing plane of the type surfaces of a slug. When particular date designations are uppermost on wheels 176, corresponding type elements are in lowermost printing positions.

A printing numbering head is indicated at 182 and is of conventional type provided with an arm 184 normally urged upwardly by a spring 186 and being arranged when depressed to advance the numbering head by one unit. For this purpose, a pin carried by the arm 184 is engaged by the forked end of a lever 188 pivoted in the box and provided with a pin 190 which is arranged to be engaged by the upper end of a slide 192 guided for vertical sliding movement in the machine frame by studs 194 and normally urged downwardly by a spring 196.

The lever 188 is connected by a link 198 to an arm depending from a shaft 200 journalled in the printing box and provided with depending fingers 202 for the purpose of ejection of slugs. These fingers are arranged to engage the slide 140 to move it forwardly.

An operator's key 204 is arranged to be inserted in the printing box and is provided with a code or other designation indicative of a particular operator of the machine, printing being effected through the medium of a type surface indicated at 206. The key 204 also serves to control operability of the machine and for this purpose is provided with a notch 208 engageable by the tapered nose of a slide 210 which is guided for horizontal sliding movement in the printing box and is normally urged toward the right, as viewed in Figure 9, by means of a spring 212. The end of the slide 210 is arranged to engage a shoulder 214 formed on a vertical slide member 216 which is slotted at 218 for its vertical guidance. An opening 220 in the lower portion of this slide which projects below the printing plane of the printing box is provided for purposes hereafter described. A projecting ear 222 is supplied at the opposite end of the printing box and is provided with a similar opening 224.

For the purpose of providing coding of tickets to indicate types of sales involved, there projects through the upper surface of the printing box a wheel 226 carrying suitable designations and geared as indicated at 228 to a printing type wheel 230 carrying type elements corresponding to the designations on wheel 226, corresponding designations and type elements being respectively uppermost and lowermost simultaneously.

The printing box also contains fixed, but replaceable, printing slugs for the printing of special data. For example, a slug 225 may be provided to print a member of code identifying the machine, and a slug 231 may be provided to print the validating signature of some authorized officer or agent of the transportation company. It will be evident that various other relatively unchangeable matters may be printed by suitably arranged slugs.

A slide 232 is slotted to embrace pins 234 and 236 secured in the frame to mount it for vertical movements. A spring 238 normally urges this slide upwardly. The upper end of this slide is arranged to be engaged by the member 216 previously mentioned when the printing box is lowered. The slide 232 has a pin and slot connection 240 with lever 28 and when the slide is depressed by the

member 216 operation of the machine is initiated by the removal of lever 28 from the lower end of lever 22.

At 242 the slide 232 has a pin and slot connection with one arm of a bell crank 244 the other arm of which is pivoted to a link 246 which is in turn pivoted to a lever 248 pivoted to the frame at 24 and arranged to be engaged by a roller 250 carried by the gear 10.

On the opposite side of the machine a slide 232' is mounted similarly to 232 and is similarly actuated through 10 bell crank 244' and link 246' from a lever 248' which is actuated upon by a stud 250' carried by a disc 10' carried by shaft 11.

The shaft 32 carries a cam 254 and is arranged to act over an extent of approximately 180° upon a follower 15 roller 256 carried by a link 258 which is slotted at 260 to embrace the shaft 32 for guidance. The link 260 is connected at its forward end at 262 with the operating arm 264 of a counter 266 which registers the number of operations of the mechanism. At its other end, the link 20 258 is pivoted at 268 to an arm 270 which is secured to a shaft 272 which carries a second arm 274 similar to 270. The respective arms have hooks at their upper ends arranged to engage within the respective openings 220 and 222 of the members associated with the printing box. A 25 spring 276 normally urges both of these arms to disengaging positions.

A lever 278 is provided with a handle 280 projecting outwardly of the machine and is pivoted at 282 to the machine frame. A link 284 connects this lever with a 30 second lever 286 pivoted at 288 to the frame and urged counterclockwise, as viewed in Figure 7, by a spring 287. At its lower end lever 286 is connected by link 292 to a lever 294 pivoted to the frame at its lower end at 296. This lever 294 is pivoted at 298, where a follower roller 35 is provided, to a slide 300 which is slotted and mounted in the frame by pins 302 and 304, being urged toward the left, as viewed in Figure 2, by a spring 306.

At its upper end, the lever 286 is provided with a roller 40 308 arranged to enter a depression in a disc 310 carried by the shaft 58.

Secured to the ear 130 of the printing box is a cam 312 which is arranged to act upon the roller 298 at the upper end of lever 294. The cam 312 is also provided with depressions 318 and 320 arranged to cooperate with a roller 45 316 mounted in the forward end of a lever 322 which is pivoted to the frame at 324 and is urged counterclockwise as viewed in Figure 2 by a spring 326. A notch 327 in the lever 322 is arranged to cooperate with a lug 329 carried by the lever 286.

50 A pin 328 on lever 286 is arranged to engage the depending arm of a bell crank 330 which is urged in a clockwise direction, as viewed in Figure 7, by a spring 331. This bell crank is carried by a shaft 333 which supports the plate 66, previously mentioned, and serves 55 to provide swinging of the free edge of plate 66 towards and from the portion of the cover plate 335 adjacent to the opening 337 thus clamping or releasing the ticket strip.

A lever 332 pivoted to the frame at 334 has its rear 60 end pivoted to the slide 192 previously referred to, and at its other end is provided with a roller 336 arranged to be acted upon by a cam 338 secured to the shaft 11.

As shown in Figure 20, the top of the machine housing is provided in front of the printing box with a ledge 340 65 the purpose of which is to prevent the removal of a printing slug S when the box is in its lowermost position. It has a bevelled forward surface which is of assistance in guiding a slug into position in the box.

An inked ribbon D passes between the two record strips 70 R and R' transversely across the machine, being supplied from a reel 342 and taken up by the reel 344 which may be manually rolled by means of a knurled roller 346 projecting upwardly through the top plate of the housing. By means of this ribbon the impressions to be recorded 75 are impressed on both record strips R and R'. To attain

this end, the ribbon D is of a type to apply ink from both of its faces and the upper record strip R is made of thin paper so that matter imprinted on its under side is visible from its top side. The strip R' may be of relatively heavier paper.

Before describing the operation of the machine, reference may be made to the construction of a typical slug S as particularly illustrated in Figures 22, 23 and 24. This slug comprises a body 350 of steel having its side edges folded at 352 and shaped to provide ridges 354 presenting angular edges arranged to seat in the bottoms of the guide grooves 172 and 174. As a result of this construction, when the strips 168 and 170 are raised and upward pressure is applied to the slug it is precisely and fixedly positioned in the printing box.

The lower edge of the body, as viewed in Figure 24, is inturned and cooperates with punched out tabs 358 to hold the printing matrix 360 which is held at its sides by lugs 366 and 368 punched outwardly from the body. The matrix, which is of the inexpensive type commonly used in addressing machines, has type elements thereon of two groups, the first, 362, arranged to print matters on tickets only, and the latter, 364, arranged to print matters on both tickets and record or journal strips. The latter, it will be noted, occupy only narrow strips on the matrices, in printing being aligned with the active type on the numbering head, the type faces on the operator's key and slug 225, and the active type on the type wheel 230.

The upper edge 370 of the body is inturned and cooperates with punched out tabs 372 and 374 and with punched out lugs 376 and 378 to hold a slug identifying card 380 on which may be printed data corresponding to the matrix, including, for ready reference by the ticket agent, the price to be charged for the ticket issued through use of the slug. A large number of these slugs may be stored in a rack in overlapping arrangement with their identifying cards 380 exposed to view.

X's as indicated in Figure 24 may be provided to fill spaces on a ticket which should not receive insertions. They serve the further purpose of providing even pressure to maintain the slug in proper printing position when the useful matter to be printed is asymmetrically located on the slug as in the particular slug illustrated.

The structure of the machine having been described, there may now be considered the operations involved in printing a ticket through the use of a slug which contains all the matters required to identify the ticket, i.e., requiring no write-in.

When the machine is in rest position, the printing box occupies a slightly tilted position as illustrated, for example, in Figures 2, 3, 6 and 20. It is retained in this position by the yielding engagement of roller 316 in the notch 318 of cam 312. The discs 176 will have been adjusted for the printing of a proper date by the printing of a proper date by the printing type wheels 180. The operator's key 204 will be in position serving to locate the end of slide 210 over the shoulder 214 of the slide 216. The operator will adjust the disc 226 to secure printing by the wheel 230 of the designation on the ticket to correspond with the type of sale involved.

The slug corresponding to the ticket desired is now introduced, matrix down and held by the edge containing the card 380, into the printing head, being guided thereto over the member 340 and under the ears 134, and being pushed into the opening between the plate 132 and the inking ribbon C. The magnets 136 will attract the slug in its inward movement, raising it upwardly so as to avoid engagement of its advancing edge with the ribbon C. Prior to the insertion of the slug, the portion 142 of slide 138 will be resting on the shoulder 154 of the link 144 which will be prevented from downward movement by the fixed pin 152 in engagement with the upper end of the slot 150. As the slug reaches its innermost position, the slide 138 will be forced rearwardly so as to clear the portion 142 from the shoulder 154, thus freeing the print-

ing box for downward movement. To effect initiation of the operation the printing box is now pressed downwardly, the roller 316 yielding to permit such movement. It may be noted that if the slug was entered upside down, the ribs 354 would prevent guides 168 and 170 from moving upwardly relatively to the printing box so that by engagement with plate 126 they would prevent sufficient downward movement of the printing box to start the machine.

- 5 10 The downward movement of the printing box produces downward movement of slide 232 against the action of spring 238 through the slide 216 which is backed up by the slide 210 because of the presence of the operator's key, the slide 216 then being, in effect, rigid with the printing box. The downward movement of the slide 232 rocks the lever 28 to release the lever 22 for movement under the action of spring 26. The gear segment 12 is thus released into mesh with the pinion 3. Simultaneously, the pin 34 acts upon the switch member 36 to cause 15 engagement of contacts 38 and thus close the circuit for 20 operation of motor 2. The result, accordingly, is rotation of the shafts 11 and 32.

The complete cycle of operation of the machine involves a single revolution of the shafts 11 and 32 which 25 are interconnected by the equal size gears 10 and 30. The first half revolution of these gears involves printing and will be referred to as the printing half cycle. The second half revolution will be referred to as the feeding half cycle.

- 30 As soon as rotation of shaft 11 begins, cam 40 acts upon follower roller 42 to maintain closed the contacts 38, releasing this roller only at the end of a complete revolution of shaft 11, thus maintaining the motor in operation through the complete cycle.

35 At the beginning of rotation of shaft 32, follower 256 is acted upon by cam 254 to advance the counter 266 and simultaneously to cause the hooked upper ends of levers 270 and 274 to engage in the openings 220 and 222 to lock the printing box in its lowered position. By 40 reason of the fact that the ledge 340 is now in front of the slug S, the slug cannot be removed. The downward movement of the printing box rocks lever 322 causing notch 327 to embrace lug 329 thus preventing removal of the roller 308 from the notch in cam 310 and effecting locking of the strip feeds. Lever 278 is held in position to prevent 45 manual disengagement of pin 80 from the notch in sleeve 82. The pinching action of plate 66 on the ticket strip is also maintained.

- 50 Eccentric 108 moves from its dead center position pulling forwardly the carriage 114. As this carriage advances toward the left, as viewed in Figures 4 and 5, the engagement of pinion 120 with fixed rack 122 produces a clockwise rotation of the platen 124 which simultaneously 55 bodily moves forwardly providing a rolling pressing action forcing the strips R', R and T against the printing faces on the slug and on the date printing head embodying the printing wheels 180, the wheels of the numbering head 182, the type face on the operator's key, the type face 230 which prints the type of sale identification and the other type faces in the printing box. At the initiation of this 60 printing movement of the platen, the slug, if not previously in precisely proper position, will be positioned by engagement of the tops of the ridges 354 with the troughs of the guide grooves 172 and 174, the guide members 170 and 168 being forced upwardly against the actions of the leaf springs 169 and 171. It may be noted that 65 due to the bodily movement of the platen 124 and its concurrent rotation imparted through the gearing from rack 122 its surface is constrained to a true rolling action without slippage so that a clear printed impression will 70 be made without smearing.

The ticket T is printed by reason of the interposition of the inked ribbon C between it and the type, and all matters appearing on the slug and the other printing surfaces will appear thereon. However, as previously noted,

it is not desired to print on the record strips all of the matters appearing on the type faces in the printing head, and printing is accordingly limited by virtue of the use of the narrow ribbon D to those matters which are of interest for record, namely, the matters at 364 on the slugs and the matters printed by wheel 230, by type faces 206 and 225, and by the numbering head.

At the end of the first half revolution of shafts 11 and 32, the eccentric 108 will have reached its forward dead center position and cam 254 will release follower 256. The result of the last operation is withdrawal of the hook upper ends of levers 270 and 274 from the openings 220 and 222. Immediately following this occurrence, roller 250 on gear 10 acts upon the lever 248 to rock bell crank 244 forcing the link 232 upwardly, if this has not already moved upwardly under the action of spring 238, thus raising the printing box to its initial tilted position wherein it is yieldingly held by engagement of roller 316 in notch 318, lever 322 concurrently releasing the lug 329. Simultaneously with this, the stud 23 will act on lever 22 to rock the lever into a position to clear the end of lever 28, with a restoration of the lever 22 to the position illustrated in Figure 3 in which it will engage the clutch controlling pin 18 when that pin reaches the end of its revolution. The clutch, however, is not disengaged nor is the switch opened, and, consequently, the rotation of shafts 11 and 32 continue through the second half cycle.

Due to the fact that the printing box is thus raised, the return of the platen by eccentric 108 is not accompanied by printing. Shortly after the beginning of the second half cycle, the cam 338 acts upon the follower 336 to produce advance of the counting head in the printing box and, simultaneously, partial forward ejection of the slug with the result that the extension 142 of slide 128 projects over the shoulder 154 of link 144 preventing downward movement of the printing box. Thus, the type is completely free from the strips.

Also at the beginning of the second half cycle, the segmental gear 48 meshes with the gear 50 to begin the drive of that gear. The number of teeth on segment 48 is equal to the total number of teeth on gear 50 and, accordingly, the half rotation of segment 48 will produce a complete rotation of gear 50. Through the chain drive, shaft 58 is now rotated, roller 308 being forced out of the notch in disc 310 which has theretofore positioned shaft 58 in a definite position. The resulting rocking of lever 286 in turn rocks bellcrank 330 moving plate 66 from ticket strip clamping position. Movement of lug 329 beyond the notch 327 prevents rocking of lever 322 which in turn prevents the printing head from being either raised or lowered. The rotation of shaft 58 through pinwheels 60 advances the ticket strip T through the distance corresponding to the length of one ticket, to project this ticket length from the top of the machine.

A considerably smaller advance is desired for the record strips R and R' and this is accomplished through the Geneva drive elements 68 and 70 and through the reduction gearing 72 and 74, the shaft 76 which drives the record strips through the sleeve 82 and pinwheels 84 imparting to it only a sufficient advance to provide a clean portion of each of the record strips in printing position. Record strip R is slightly advanced through the opening constituted by the guides 88 and 90 while the record strip R' is advanced for reception in the receiving bin 98.

At the end of the second half cycle, the segment 48 releases gear 50 thereby interrupting the feed. The rotation of the shaft 58 will be such as to bring the notch in disc 310 into cooperation with the roller 308 and the action of the spring 287 will serve to produce such slight adjusting rotation as is required to bring the shaft 58 into proper rest position. At the end of the cycle, the pin 18 will be arrested by the lower end 20 of lever 22 disengaging the gear segment 12 from pinion 8. At 75

the same time, follower 42 will be released by cam 40 thus opening the energizing circuit of motor 2. The parts are thus brought into their initial rest position ready for a repetition of the cycle upon initiation as above described.

5 When roller 308 drops into the notch in cam 310, bellcrank 330 rocks under the action of spring 331 to effect clamping of the ticket strip by plate 66 against the edge of plate 335 forward of the slot 337 through which the ticket strip is fed, thus providing gripping which facilitates tearing off of the issued ticket.

10 Certain interlocks are involved in the mechanism as already described and as follows. If the shaft 58 either does not arrive at its final proper position or is displaced from such position, the lever 286 will be displaced with the result that through lever 294 the slide 300 will be projected under the square lug 252 carried by the slide 232 with the result that the printing box cannot be depressed to initiate the operating cycle. The same result occurs if the lever 278 is manipulated by handle 280 to free the shaft 76 for sliding movement against the action of spring 78 to release its connection through pin 80 with the sleeve 82. Such a release is desirable when one or both of the record strips is to be pulled outwardly or during threading. But under such conditions of release of the record strips, the machine must be incapable of operation, and, hence, only when the lever 278 is in an interposing position to prevent disengagement between the shaft 76 and sleeve 82 should the machine be in condition for a ticket printing and issuing operation.

15 30 In the event that it is desired to provide a write-in ticket, the printing box 128 may be lifted to a higher position as illustrated in Figure 19 to give access to the ticket strip so that a written notation of suitable type may be made thereon. Under these conditions, the cam 312 acts upon the follower roller 298 to project the slide 300 under the lug 252 to prevent operation of the machine by the insertion of some implement which might move downwardly the slide 232. Except when the printing box 128 is raised, this cannot be done inasmuch as the printing box closes the opening in the top of the machine housing through which access may be had to the slide 232.

35 The printing box 128 is yieldingly held in its raised position for the writing of data on a ticket by engagement of notch 320 with roller 316.

40 45 Following the making of a written notation on a ticket, the machine is operated to issue the ticket by restoring the printing box to its normal slightly tilted position and inserting a slug which will identify the fact that a write-in ticket has been issued. From this point on the operation 50 is as described above for the issuance of a ticket the information on which is completely printed by the machine.

55 Reference may now be made to illustrative ticket issuing and accounting operations performed by the described machine which may be operated for various different practices.

First, there may be considered what is involved in the issuance of relatively simple tickets such as one-way tickets or round-trip tickets involving simple accounting procedures.

60 60 In such a case, a single ticket strip T may be fed through the machine. Such ticket strip is illustrated in Figure 21 and comprises a central portion 400 together with side strips 402 containing the feed holes 404 and 406 designed for engagement by the pinwheels 60.

65 65 Demarcation between the strips 402 and the central portion 400 of the ticket strip is effected by perforated lines 408 along which tearing takes place in the ticket issuing operation by reason of the guard members 64 previously described, the severed edge portions designated T' in 70 Figure 18 being retained in the machine. A line of perforations 408 which are not torn in the machine may separate the central portion of the ticket strip into two parts which are detachable in the finished ticket to provide either a receipt stub or single trip stubs of a round-trip ticket.

Transverse lines of perforation indicated at 410 are provided and the issued tickets are torn off along these lines while the ends of the ticket strip appearing in successive operations are clamped by the plate 66. While there has been disclosed this matter of tearing off the individual tickets, it will be evident that the machine with added complexity may be made to cut off the issued tickets automatically. However, consistent with simplicity, it is thoroughly satisfactory to provide an arrangement in which the tickets are manually torn off.

The ticket strip T may be preprinted in various fashions of which that illustrated in Figure 21 is typical. It may contain, for example, identification of the transportation company as indicated at 412 and for checking of proper procedures in issuing tickets it is desirable that the ticket areas be numbered serially as at 414 and 416, the same number desirably appearing on the areas which form ultimately separable stubs. Such other invariable matters as may be useful may also be printed as, for example, at 418, to indicate an area in which a date might be written if the ticket is not to be valid before a particular date.

Boxes 420 and 422 for the reception of matters printed in the machine may be provided for use under some conditions, whereas under others the boxes may have no particular significance. There may also be printed legends such as indicated at 424 to identify matters which are printed in the machine.

Reference may next be made to Figure 25 which illustrates at 426 the matters printed by the particular matrix shown in Figure 24. These printed matters comprise the following:

At 428 and 430 there are indicated, respectively, the places of origin and destination of the trip for which the ticket is issued. At 432 there is printed matter identifying the type of trip involved and conditions which may apply to the purchase of the ticket. The code designation associated with the trip and the particular matrix used is printed at 434. At 436 there is indicated the type of transportation involved. At 438, 440 and 442 there are indicated, respectively, the fare and tax and the total price of the ticket. At 443 there may be printed certain accounting or statistical data which may have no particular meaning on the face of the ticket but which may be desirably involved in the accounting record. At 444 and 446 there are indicated X's which serve to blank out areas of the ticket to prevent fraudulent insertion of other data and which, as described above, are also involved in the mechanical aspect of preventing tilting of the slug during the printing operation when the useful type faces on the slug are more or less asymmetrically arranged.

Figures 21 and 25 may now be considered in association with Figure 28 which illustrates a ticket issued by the machine and resulting from printing involving the slug of Figure 24 on the ticket strip illustrated in Figure 21. The ticket, as will be evident, embodies the pre-printed matters on the ticket strip and the matters printed by the slug matrix. Additionally printed on the ticket are the number 448 printed by the numbering head in the printing box, the designations 450 and 452 printed by the slug identifying the machine and the operator's key, and the type of sale identification 454 printed by the wheel 230. Additionally printed at 456 is the matter appearing on the slug 231, for example, as illustrating the validating signature of an officer or agent of the transportation company. Printed also at 457 by the dating head is the date of issuance.

The ticket illustrated in Figure 28 is typical of a one-way fare ticket. Simple round-trip ticket printing merely by the use of a different slug is illustrated at 458 in Figure 29. The two stubs in this ticket correspond to the individual one-way trips and in the boxes 420 and 422 there printed the origins and destinations of the separate one-way trips as at 460 and 462.

Other printing data different from that involved in the

ticket of Figure 28 is illustrated at 466 and 468. Special accounting or statistical data may be printed at 470 so as to appear on a record sheet in a different column from that printed at 443 in Figure 28.

5 A typical record sheet R (duplicated in the record sheet R') is illustrated in Figure 33. The record strip is provided with edge perforations 472 which are engaged by the pinwheels 84. Examination of what is printed in Figure 33 will reveal that the line of data indicated at 474 corresponds to that printed at the bottom of the ticket of Figure 28, while the line of data indicated at 476 corresponds to that printed at the bottom of the ticket illustrated in Figure 29. Legends at the top of Figure 33 indicate typical significance of the items printed in the first columns in Figure 33, while the legends indicated at 478 indicate the significance of the line representing the type of sale. These lines, in various instances, indicate matters which should be taken into account in the evaluation of the record strip. For example, in the line indicated at 479, the ticket issued would be printed by a matrix generally applicable to the coach trip involved. This matrix would normally indicate the tax on the trip. But the designation "GX" indicated at 480 shows that this particular ticket was issued on government order and was, therefore, tax exempt. Consequently, in evaluating the data, the tax in this instance would have to be deducted in conforming the cash account of the ticket agent with the record. Similarly, in line 481 there appears the letter E indicating that the ticket there issued was in exchange for another ticket and suitable account would have to be taken of that fact.

Line 482 indicates the issue of a write-in ticket for which no individual slug was provided, the issuance of this ticket involving the writing in of data by the ticket agent as described above including the items of net fare, tax and total fare which appear written in on the record. As described above, slugs would be provided to identify the issuance of write-in tickets of various classifications but not identifying trips of some unusual connections.

40 The ticket issued corresponding to the entry in line 482 (which indicates issuance of a round-trip ticket) would resemble that shown in Figure 29 except that the stations would be written in as well as the fare and tax data shown in Figure 33.

45 The issuance of a more elaborate interline round-trip ticket is illustrated in the matters appearing in Figures 26, 30, 31 and 32.

The desire here is to issue in a single operation a ticket containing in the particular example illustrated six 50 coupons each good for a section of a round-trip involving three separate transportation lines. The final ticket which is issued is illustrated in Figure 32 as comprising the three sections, each providing two coupons designated 484, 486 and 488 shown detached in Figure 32 but which 55 would ordinarily be stapled together following issuance. The matrix of the slug used for the issuance of such a ticket is arranged to print the matters illustrated in Figure 26 at 490. Among these printed matters, with which are included matters of types previously described and 60 which need not be redescribed, are station and transportation company designations indicated at 516 and 518.

In the issuance of this ticket there is not only involved a ticket area of the ticket strip T of Figure 21 but two additional ticket sheets 492 and 494 illustrated in Figures 65 30 and 31 and containing the preprinted matters indicated in these figures. Ordinarily, this pair of sheets would be secured together in the regions of stubs 496 and 498 which are separable along the perforated lines 500 and 502. The sheets 492 and 494 in this case would be carbon backed throughout the area thereof which involved printing. In the operation of the machine, these sheets attached together would be placed over the window 495 in the top plate of the machine illustrated in Figure 17, being superimposed on the ticket strip T, while the printing box was raised to the position illustrated in

Figure 19. The printing box would then be lowered and the slug 490 inserted and operation effected in the usual way, the sheets 492 and 494 being removed as well as the ticket area of the strip T and ultimately stapled together.

Included in the matter preprinted on the sheets 492 and 494 are boxes 504, 506, 508 and 510 with the residual areas on which would be printed the station and transportation company identifications blacked out. While all of the station and transportation line designations are printed on all of the group consisting of the sheets 492 and 494 and the ticket area of strip T, the blacking out of areas will leave on the coupons of the sheets 492 and 494 only the designations pertaining to the individual coupons. It will be noted that the designations corresponding to the coupons resulting from ticket strip T are incorporated in the boxes 420 and 422. Preprinted designations of the coupon numbers in order of use appear on sheets 492 and 494.

The line of data at 522 in Figure 33 corresponds to the issuance of this interline round-trip ticket.

Figures 27, 34, 35 and 36 are illustrative of another typical operation of the machine in this case for the issuance of Pullman accommodation tickets.

For this purpose, instead of a single-ply ticket strip such as has been previously discussed, there is utilized a triple-ply strip T' of which each ply is generally similar to the single-ply ticket strip to which reference has heretofore been made. The top ply is indicated at 524 and from this office record coupons are provided. The intermediate ply 526 gives rise to conductor's coupons. The third ply 528 gives rise to coupons constituting passenger receipts.

At the left-hand and right-hand edges of the sheets are the perforated feeding strips 530 and 534 delimited by perforated lines 532 and 536, respectively. The individual coupon areas are divided by perforated lines 538 which, in this instance, are desirably continued as at 540 across the left-hand edge portions 530. In this instance, the three-ply strip is desirably fed through the machine in such fashion that while the right-hand feeding strip portions 534 are fed beneath the right-hand guide 64 so as to be torn off automatically in issuance, the left-hand feeding strip portions 530 are fed over the top of the left-hand guide 64 so as not to be severed. The three plies are desirably adhered together along their left-hand and right-hand edges and, when the ticket issues, the coupons will be secured together at their left-hand edges because of the non-removal of the edge portions 530.

The uppermost ply 524 is carbon backed at least over the entire area on which printing or writing is to occur. The same is true of the ply 526.

The various sheets of the ticket strip may be suitably preprinted in various fashions as indicated in Figure 34 and, particularly, it is desirable to provide boxes for the writing in of pertinent information. Box 542 is arranged to contain the designation of the accommodation involved. Box 544 is arranged to contain the date on which the reservation is to be used. Box 546 is to receive the car number. Box 548 is to receive the time of departure of the train.

In the issuance of the ticket the pertinent matters are written into the boxes just mentioned with the printing box in its uppermost position. The printing box is then lowered to its slightly tilted position and there is inserted a slug to print the matters indicated at 550 in Figure 27, for example, the origin and destination designations 552 and 554, the type of accommodation involved as at 556, and the trip identification price data, etc., as indicated at 558.

The operation of the machine with this slug will give rise to a ticket of three coupons such as is indicated in Figure 35. In this figure, the various coupons are shown detached and are essentially duplicates providing a passenger's receipt 560, conductor's coupon 562

and an office record 564. The written in information comprises at 566 the identification of the space, at 568 the date for use of the ticket, at 570 the car number and at 572 the time of departure of the train.

5 Figure 36 indicates at 574 the record which is made of pullman reservation sales. It will be noted that in line 576 of this record there is printed the data corresponding to the issuance of the ticket of Figure 35.

Figure 37 illustrates a commutation ticket which may 10 be issued by the machine. For this purpose there may be superimposed over the strip shown in Figure 21 a coupon 578 having preprinted thereon certain data common to numerous commutation tickets to be issued, such as the heading 580, the number of trips for which they are usable as at 582, conditions of use as at 584, the time limit as at 586, and the trip numbers and punching locations as at 588 and 590. Operation then 15 takes place as above described using a slug which will print the stations 592, and the matters to appear on the record strips as at 594. The date 596, the validating signature 598, the ticket number 600, the seller and machine numbers 602, and the type of sale indication 604 will be printed by the machine as usual.

Since the coupon 578 will not be carbon backed, none 20 of this data will be printed on the ticket strip shown in Figure 21 but in the operation there will be issued a blank coupon from this strip which may be discarded. The matter appearing at the bottom of the ticket will, of course, be recorded on the record strips R and R'.

30 Since for proper printing of the record strips the stock used for coupon 278 is relatively light, the commutation ticket coupon, after printing, may be adhered to a cardboard backing before presentation to the purchaser.

It will be evident from the foregoing description that 35 the machine described may be used for many purposes other than the issue of transportation tickets.

What is claimed is:

1. In a business form issuing machine, means for 40 guiding and advancing a form strip, means for guiding and advancing a record strip in overlapping relationship with said form strip through a printing zone, a carrier for receiving and positioning a type member, said carrier being movable approximately at right angles to the portions of said strips in said printing zone whereby a 45 type member in the carrier may be located adjacent to, but spaced from, said strips in non-printing position or close to said strips in printing position, means for effecting printing of both of said strips by a type member in the last mentioned position, means for controlling a cycle of operation of said machine to effect such printing and predetermined advance of both of said strips, and means initiating operation of said controlling means responsive to manual movement of said carrier to move the type member therein from the first to the second 55 mentioned position.

2. In a business form issuing machine, means for 60 guiding and advancing a form strip, means for guiding and advancing a record strip in overlapping relationship with said form strip through a printing zone, a carrier for receiving and positioning a type member, said carrier being movable approximately at right angles to the portions of said strip in said printing zone whereby a type member in the carrier may be located adjacent to, but spaced from, said strips in non-printing position or close to said strips in printing position, means for effecting printing of both of said strips by a type member in the last mentioned position, means for controlling a cycle of operation of said machine to effect such printing and predetermined advance of both of said strips, and means initiating operation of said controlling means 65 responsive to manual movement of said carrier to move the type member therein from the first to the second mentioned position, said controlling means effecting location of the type member in the first mentioned position during advance of at least one of said strips.

3. In a business form issuing machine, means for guiding and advancing a form strip, means for guiding and advancing a record strip in overlapping relationship with said form strip through a printing zone, a carrier for receiving and positioning a type member, said carrier being movable approximately at right angles to the portions of said strips in said printing zone whereby a type member in the carrier may be located adjacent to, but spaced from, said strips in non-printing position or close to said strips in printing position, means for effecting printing of both of said strips by a type member in the last mentioned position, means for controlling a cycle of operation of said machine to effect such printing and predetermined advance of both of said strips, said carrier being movable to a third position in which a type member is substantially spaced from said strips thereby to provide a clearance for the manual writing of data on said strips, and means initiating operation of said controlling means responsive to manual movement of said carrier to move the type member therein from the first to the second mentioned position.

4. In a business form issuing machine, means for guiding and advancing a form strip, means for guiding and advancing a record strip in overlapping relationship with said form strip through a printing zone, a carrier for receiving and positioning a type member, said carrier being movable approximately at right angles to the portions of said strips in said printing zone whereby a type member in the carrier may be located adjacent to, but spaced from, said strips in non-printing position or close to said strips in printing position, means for effecting printing of both of said strips by a type member in the last mentioned position, means for controlling a cycle of operation of said machine to effect such printing and predetermined advance of both of said strips, said carrier being movable to a third position in which a type member is substantially spaced from said strips thereby to provide a clearance for the manual writing of data on said strips, and means initiating operation of said controlling means responsive to manual movement of said carrier to move the type member therein from the first to the second mentioned position, said controlling means effecting location of the type member in the first mentioned position during advance of at least one of said strips.

5. In a business form issuing machine, means for guiding and advancing a form strip, means for guiding and advancing a record strip in overlapping relationship with said form strip past a printing zone, means for positioning a type member in printing relationship with said strips in said zone, means for effecting printing of both of said strips by a positioned type member including means providing in juxtaposition with said record strip in said printing zone an inking member having an effective area substantially less than the printing area of the type member so that said record strip will be printed by a lesser area of the slug than that which prints said ticket strip, and means for controlling a cycle of operation of said machine to effect such printing by a positioned type member and predetermined advance of both of said strips.

6. In a business form issuing machine, means for guiding and advancing a form strip, means for guiding and advancing a record strip in overlapping relationship with said form strip past a printing zone, means for positioning a type member in printing relationship with said strips in said zone, means for effecting printing of both of said strips by a positioned type member including means providing in juxtaposition with said record strip in said printing zone an inking member having an effective area substantially less than the printing area of the type member so that said record strip will be printed by a lesser area of the slug than that which prints said ticket strip, and means for controlling a cycle of operation of said machine to effect such printing by a positioned type member and predetermined advance of both

of said strips, with advance of said record strip substantially less than the advance of said ticket strip.

7. In a business form issuing machine, means for guiding and advancing a form strip having edge portions thereof containing feeding openings and with said edge portions differentiated from the central portions of the strip by weakened lines, said means including means providing projections engageable with said openings to feed the strip, means for guiding and advancing a record strip in parallelism with said form strip, means for positioning a type member in printing relationship with said strips, means for effecting printing of both of said strips by a positioned type member, means controlling a cycle of operation of said machine to effect such printing by a positioned type member and advance of both of said strips, and means for removing said edge portions of the ticket strip during its advance.

8. In a business form issuing machine, means for guiding and advancing a form strip having edge portions thereof containing feeding openings and with said edge portions differentiated from the central portions of the strip by weakened lines, said means including means providing projections engageable with said openings to feed the strip, means for guiding and advancing a record strip in parallelism with said form strip, means for positioning a type member in printing relationship with said strips, means for effecting printing of both of said strips by a positioned type member, means controlling a cycle of operation of said machine to effect such printing by a positioned type member and advance of both of said strips, and means for removing at least one edge portion of the ticket strip during its advance.

9. In a business form issuing machine, means for guiding and advancing a form strip having edge portions thereof containing feeding openings and with said edge portions differentiated from the central portions of the strip by weakened lines, said means including means providing projections engageable with said openings to feed the strip, means for guiding and advancing a record strip in parallelism with said form strip, means for positioning a type member in printing relationship with said strips, means for effecting printing of both of said strips by a positioned type member, means controlling a cycle of operation of said machine to effect such printing by a positioned type member and advance of both of said strips, and means for removing at least one edge portion of the ticket strip during its advance.

10. In a business form issuing machine, means for guiding and advancing a form strip having edge portions thereof containing feeding openings and with said edge portions differentiated from the central portions of the strip by weakened lines, and having weakened lines differentiating successive form areas of said central portion, said means including means providing projections engageable with said openings to feed the strip, means for guiding and advancing a record strip in parallelism with said form strip, means for positioning a slug in printing relationship with said strips, means for effecting printing of both of said strips by a positioned slug, means controlling a cycle of operation of said machine to effect such printing by a positioned slug and advance of both of said strips, and means for removing said edge portions of the ticket strip during its advance.

11. In a business form issuing machine, means for guiding and advancing a form strip having edge portions thereof containing feeding openings and with said edge portions differentiated from the central portion of the strip by weakened lines, and having weakened lines differentiating successive form areas of said central portion, said weakened lines terminating short of said edge portion, said means including means providing projections engageable with said openings to feed the strip, means for guiding and advancing a record strip in parallelism with said form strip, means for positioning a type mem-

ber in printing relationship with said strips, means for effecting printing of both of said strips by a positioned type member, means controlling a cycle of operation of said machine to effect such printing by a positioned type member and advance of both of said strips, and means for removing said edge portions of the ticket strip during its advance.

12. In a business form issuing machine, means for guiding and advancing a form strip, means for guiding and advancing a record strip in overlapping relationship with said form strip through a printing zone, a carrier for receiving and positioning a type member, means mounting said carrier for movement approximately at right angles to the overlapping portions of said strips in said printing zone whereby a type member in the carrier may be located adjacent to, but spaced from, said strips in non-printing position or close to said strips in printing position, means for effecting printing of both of said strips by a type member in the last mentioned position, and means for controlling a cycle of operation of said machine to effect such printing and predetermined advance of both of said strips, said controlling means effecting location of the type member in the first mentioned position during advance of at least one of said strips.

13. In a business form issuing machine, means for guiding and advancing a form strip, means for guiding and advancing a record strip in overlapping relationship with said form strip through a printing zone, a carrier for receiving and positioning a type member, means mounting said carrier for movement approximately at right angles to the overlapping portions of said strips in said printing zone whereby a type member in the carrier may be located adjacent to, but spaced from, said strips in non-printing position or close to said strips in printing position, means for effecting printing of both of said strips by a type member in the last mentioned position, the last mentioned means comprising a platen having a rolling motion relative to said strips and type member to apply progressive pressure to successive limited areas thereof, and means for controlling a cycle of operation of said machine to effect such printing and predetermined advance of both of said strips.

14. In a business form issuing machine, means for guiding and advancing a form strip, means for guiding and advancing a record strip in overlapping relationship with said form strip through a printing zone, a carrier for receiving and positioning a type member, means mounting said carrier for movement approximately at right angles to the overlapping portions of said strips in said printing zone whereby a type member in the carrier may be located adjacent to, but spaced from, said strips in non-printing position or close to said strips in printing position, means for effecting printing of both of said strips by a type member in the last mentioned position, the last mentioned means comprising a platen having a rolling motion relative to said strips and type member to apply progressive pressure to successive limited areas thereof, means for locking said carrier to hold the type member in the last mentioned position during said printing, and means for controlling a cycle of operation of said machine to effect such printing and predetermined advance of both of said strips.

15. In a business form issuing machine, means for guiding and advancing a form strip, means for guiding and advancing a record strip in overlapping relationship with said form strip through a printing zone, a carrier for receiving and positioning a type member, means mounting said carrier for movement approximately at right angles to the overlapping portions of said strips in said printing zone whereby a type member in the carrier may be located adjacent to, but spaced from, said strips in non-printing position or close to said strips in printing position, means for effecting printing of both of said strips by a type member in the last mentioned position, means for positioning an additional sheet to be printed in said

printing zone in superposed position over said ticket strip and beneath a type member, and means for controlling a cycle of operation of said machine to effect such printing and predetermined advance of both of said strips.

16. In a business form issuing machine, means for guiding and advancing a form strip, means for guiding and advancing a thin record strip in overlapping relationship with said form strip past a printing zone, means for positioning a type member in printing relationship with said strips in said zone, means for effecting printing of both of said strips by a positioned type member including means providing in juxtaposition with said record strip in said printing zone and on the side of record strip opposite the type member an inking member having an effective area substantially less than the printing area of the type member so that said record strip will be printed by a lesser area of the slug than that which prints said ticket strip, whereby said record strip is printed on the side opposite the type member with characters to be read through the record strip, and means for controlling a cycle of operation of said machine to effect such printing by a positioned type member and predetermined advance of both of said strips.

17. In a business form issuing machine, means for guiding and advancing a form strip, means for guiding and advancing a record strip in overlapping relationship with said form strip past a printing zone, means for positioning a type member in printing relationship with said strips in said zone, means for effecting printing of all of said strips by a positioned type member including means providing between said record strips in said printing zone an inking member having an effective area substantially less than the printing area of the type member so that said record strips will both be printed by a lesser area of the slug than that which prints said ticket strip, whereby one of said record strips is printed on the side opposite the type member with characters to be read through the record strip and the other is printed on the side towards the type member, and means for controlling a cycle of operation of said machine to effect such printing by a positioned type member and predetermined advance of all of said strips.

18. In a business form issuing machine, means for guiding and advancing a form strip, means for guiding and advancing a record strip in overlapping relationship with said form strip past a printing zone, means for positioning a type member in printing relationship with said strips in said zone, means for effecting printing of all of said strips by a positioned type member including means providing between said record strips in said printing zone an inking member having an effective area substantially less than the printing area of the type member so that said record strips will both be printed by a lesser area of the type member than that which prints said ticket strip, whereby one of said record strips is printed on the side opposite the type member with characters to be read through the record strip and the other is printed on the side towards the type member, and means for controlling a cycle of operation of said machine to effect such printing by a positioned type member and predetermined advance of all of said strips, with advance of said record strips substantially less than the advance of said ticket strip.

19. A business form issuing machine comprising means establishing a printing area, means for positioning a type member above and in printing relationship to said printing area and movable to clear the region above said printing area, means providing a movable backing element below said printing area to permit manual writing on sheet material located in said printing area when said type member positioning means clears the region above said printing area, and means effecting printing by a positioned type member of sheet material located in said

printing area and movement of said backing element from beneath said printing area during printing.

20. A business form issuing machine comprising means establishing a printing area, means for positioning a type member above and in printing relationship to said printing area and movable to clear the region above said printing area, means providing a movable backing element below said printing area to permit manual writing on sheet material located in said printing area, said backing element being normally in a position to interfere with printing, and means including a platen having a rolling movement with respect to a positioned type member for effecting printing of sheet material located in said printing area and movement of said backing element from beneath said printing area to provide clearance for the advance of said platen.

21. A form issuing machine comprising means for guiding and advancing a sheet member, means for guiding and advancing a record strip in close flatwise proximity to said member, means for positioning a type face in printing relationship with said member and said strip, means for effecting simultaneous printing of both said member and said strip by a positioned type face with printing by a portion of said type face of both said member and said record strip, means controlling printing by a positioned type face so that the type face prints a substantially greater area of said member than the area of the record strip printed thereby, and means controlling a cycle of operation of said machine to effect such simultaneous printing by a positioned type face and predetermined advances of both said member and said strip, with advance of said record strip less than the advance of said member.

22. In a business form issuing machine, means for

guiding and advancing a form strip, means for guiding and advancing a record strip in overlapping relationship with said form strip through a printing zone, a carrier for receiving and positioning a type member, means 5 mounting said carrier for movement approximately at right angles to the overlapping portions of said strips in said printing zone whereby a type member in the carrier may be located adjacent to, but spaced from, said strips in non-printing position or close to said strips in printing position, means for effecting printing of both of said strips by a type member in the last mentioned position, means for controlling a cycle of operation of said machine to effect such printing and predetermined advance of both of said strips, and a backing member below said strips, said mounting means mounting the carrier for movement to a third position in which a type member is substantially spaced from said strips thereby to provide a clearance for the manual writing of data on said strips backed by said backing member.
